(57) **CLAIM**

The ornamental design for an energy storage cabinet outdoor as shown and described.

DESCRIPTION

1. Energy storage cabinet outdoor

1.1 is a front, right, bottom perspective view of an energy storage cabinet outdoor according to the present application;

1.2 is a front view thereof;

1.3 is a rear view thereof;

1.4 is a left side view thereof;

1.5 is a right side view thereof;

1.6 is a top view thereof;

1.7 is a bottom thereof;

1.8 is an enlarged view of 1.6;

1.9 is an enlarged view of a portion of 1.2;

1.10 is an enlarged view of a portion of 1.5; and

1.11 is an enlarged view of another portion of 1.5.

Broken lines in the figures depict portions of the energy storage cabinet outdoor that form no part of the claimed design. Additional broken lines, curvy lines and numbers in figures 1.2, 1.5 and 1.6 are to demarcate areas shown enlarged in other figures and are not part of the claimed design.
